6 Claims. (Cl. 251—322)

ABSTRACT OF THE DISCLOSURE

Apparatus for detecting and filling with a wood filler voids formed in the side edges of a plywood sheet as the edge of the sheet is moved in juxtaposition relative to the apparatus, the apparatus including a combined void sensing and valve actuator means to control filler flow discharge from the apparatus to the void at substantially the void sensing means.

This invention relates to valves and valve holders, and more particularly to a valve having a mechanical sensing means which controls the flow of fluid material through the valve.

The valve and valve holder of the instant invention is particularly adapted for use in plywood finishing machines, such as is disclosed in co-pending application Serial No. 403,995, filed October 15, 1964, the disclosure of which is incorporated herein by reference. As disclosed in this co-pending application, and as partially disclosed herein, a machine is provided for filling voids in side edges of plywood sheets that occur during the manufacture thereof. Basically, such a void filling machine comprises a means for propelling a plywood sheet along a given path, a means for detecting voids that occur in side edges thereof, a supply of wood filler or the like, means for delivering the wood filler to a valve, and a valve actuated by the sensing means to deliver the wood filler to the appropriate location.

Although the valve and sensing means disclosed in the co-pending application adequately forms its desired task, it has been found that certain disadvantages reside in the sensing means and valve means of the structure of the co-pending application which is primarily due to the number of elements necessary for its operation.

It is a primary object of this invention to provide a valve and sensing means having a minimum number of moving parts.

Another object of this invention is to incorporate both a sensing means and a valve means in the same structure.

Another object of this invention is to provide a valve means and valve holder for use in a void filling machine.

It is another object of the instant invention to provide a simple, durable, compact valve and sensing means which is particularly adapted for use in a void filling machine.

Another object of this invention is to provide a valve and sensing means which is inexpensive to make and which requires little maintenance.

Other objects and advantages of the instant invention reside in the combinations of elements, arrangements of parts, and features of construction and operation, all as will be more fully pointed out hereinafter and disclosed in the accompanying drawings wherein there is shown a preferred embodiment of this inventive concept.

In the drawings:

FIGURE 1 is a fragmentary top plan view of three combination and detection filling units utilizing the valve of the instant invention, a portion of a plywood sheet being shown in dotted lines, this view being substantially the same as FIGURE 1 in the co-pending application;

2

FIGURE 2 is a cross-sectional view taken substantially along line 2—2 of FIGURE 1 and viewing in the direction of the arrow, this view being substantially the same as FIGURE 2 of the co-pending application;

5 FIGURE 3 is an enlarged cross-sectional view of the valve, sensing means and valve holder of the instant invention, the valve being shown in the fluid delivery position;

FIGURE 4 is a bottom view of the valve, sensing means and valve holder of the instant invention;

10 FIGURE 5 is a cross-sectional view taken along line 5—5 of FIGURE 3 and viewing in the direction of the arrows;

FIGURE 6 is a cross-sectional view similar to FIGURE 3 showing the valve in its normally closed position when 15 a plywood sheet is engaging the sensing means;

FIGURE 7 is a cross-sectional view similar to FIGURE 3 showing the valve in a closed position when no plywood sheet is being processed;

FIGURE 8 is a front view of the valve of the instant 20 invention showing the valve in a closed position; and

FIGURE 9 is a rear view of the device of FIGURE 8.

Referring now to the drawings, wherein like reference characters designate like elements throughout the several views thereof, a device for detecting and filling voids in 25 side edges of plywood sheets is shown generally at 20 and comprises a support means indicated generally at 22. Support means 22 comprises a horizontal platform 23 for slidably receiving a sheet of plywood material 24 or the like which may be propelled by separate motive means 30 (not shown) or which may be directly fed from plywood press or sander (not shown). Support means 22 also comprises a hold-down means generally indicated at 28 for maintaining plywood sheet 24 against platform 23 as shown in FIGURE 2.

30 Indicated generally at 30 is the filling means of the instant invention which is shown in FIGURE 1 as juxtaposed to the side edges of sheet 24. As more fully explained hereinafter, each of filling means 30 may be positioned along a separate ply of plywood sheet 24.

35 Referring now to FIGURES 3 to 9 inclusive, filling means 30 comprises a valve holder shown generally at 32 and a valve indicated generally at 34. Valve holder 32 comprises a block of material 36 which is preferably metal and which comprises a substantially rectangular body having an upper surface 38, a lower surface 40, and lateral faces indicated generally at 42, 44. Each of lateral faces 42, 44 provides a downwardly facing shoulder 46, 48 and an indented portion 50 for engagement with a holder 52 as shown in FIGURE 1, so that filling means

40 50 may be positioned in the proper location. Disposed centrally of block 36 and communicating between surfaces 38, 40 is an opening generally indicated at 53 having a lower end portion 54, an upper enlarged end portion 56 and an annular shoulder 58 created by the difference in 45 diameters of the end portions 54, 56.

50 The upper end of the portion 56 adjacent surface 38 is provided with screw threads 60. Located adjacent the lower end portion 54 and providing communication between lower end portion 54 and surface 40 is a downwardly facing opening 62 which is arcuate at its upper but which communicates with surface 40 through a rectangular opening 64.

55 Block 36 also has formed therein a second aperture perpendicular to opening 53 and indicated generally at 66 comprising an outer smooth portion 70 and an inner threaded portion 68 communicating between lateral face 50 and lower end portion 54 of the opening 53.

60 Valve 34 comprises an inner preferably cylindrical member 72 but which may be square, hexagonal or the

like, which has a blind opening 74 therein closed at its lower end by plate 75. A transverse slot 76 is cut, as by a metal saw, in the lower end of member 72 above plate 75 thus providing a means of communication between opening 74 and the exterior of member 72. Member 72 also comprises a vertically disposed arcuate slot 78 at its lower end on a side opposite from slot 76, a sensing means or blade 80 dependently secured to plate 75, and threads 82 on the upper end thereof.

As shown in FIGURES 3, 6 and 7, plate 75 provides a horizontal surface 77 underlying opening 74 and slot 76 with an upwardly angled surface 79 underlying arcuate slot 78, which facilitates the insertion of valve 34 in opening 53 since member 72 may be rotated so that ball detent 90 first engages surface 79 and then slot 78. By assembling valve 34 in a vertical position, the rotation of member 72 will allow the effects of gravity to facilitate assembly.

Although it is possible to position slot 76 immediately above sensing means 80, thus obviating the need of slots 62, 64 in holder 36, it has been found that wood filler material will be more expeditiously delivered with the illustrated embodiment.

Slidably fitted on the lower end of cylindrical member 72 is a first sleeve means 84 which extends from shoulder 58 to lower surface 40 of valve holder 32. Sleeve 84 comprises a transverse slot 86 communicating with downwardly facing opening 62 and, as shown in FIGURE 3, is aligned between slot 76 and opening 62. Sleeve 84 also comprises a circular opening 88 aligned with opening 66 in block 36.

Sleeve 84 is held in place by the coaction of opening 88 and a ball detent 90 which is fixed in opening 88 by a set screw 94. Opening 88 is preferably sized such that ball detent 90 is normally spaced from arcuate slot 78 as shown in FIGURE 5. Such a spaced relationship avoids undue frictional binding which would result from a close juxtaposition of slot 78 and ball 90. The movement of blade or sensing means 80 will act much like a castor wheel and tend to keep members 72, 88 aligned. It will be seen, however, that the rotation of member 72 is effectively precluded by the coaction of ball detent 90 and the edges of slot 78 which are, in effect, a guide means for creating substantially linear sliding movement of member 72.

Slidably fitted on the upper end of cylindrical member 72 is a second sleeve means 96 having threads 98 on the lower end thereof for engagement with threads 60 of block 36.

A biasing means indicated generally at 100 urges cylindrical member 72 in a downwardly direction and comprises a lower snap ring 102 affixed in a convenient slot of member 72, a shrink fit washer 104 positioned directly above snap ring 102, and a helical spring 106 abutting the upper surface of washer 104 and the lower surface of upper sleeve 96. It will be seen that snap ring 102 cooperates with shoulder 58 to form a limit on the downward movement of member 72.

Secured to threads 82 of cylindrical member 72 are a series of connections 108, 110, 112, which may be of any desired type, providing a means of communication between cylindrical members 72 and a pressurized source of wood filler material or the like.

In the operation of filling means 30, the unit is placed adjacent the moving plywood sheets 24 such that sensing means 80 lies on a single ply of plywood sheet 24 with sheet 24 moving from left to right in FIGURE 3 so that opening 64 lies rearwardly of sensing means 80. When the ply has no void therein, sensing means 80 will be flush with lower surface 40 as shown in FIGURE 6 such that slots 76, 86 are dis-aligned thus precluding the flow of pressurized wood filler material therethrough.

When a void occurs in the side edge of sheet 24, sensing means 80 will be pressed thereinto by biasing means

100 thus aligning slots 76, 86, as shown in FIGURE 3 allowing the flow of pressurized wood filler material through cylindrical member 72 and opening 64 into the void in sheet 24. When the void in sheet 24 passes sensing means 80, cylindrical member 72 will be cammed upwardly by the action of sensing means 80 and the edge of sheet 24.

When sheet 24 is removed from holding means 22 biasing means 100 of valve 34 will act to press member 72 downwardly such that slots 76, 86 are again dis-aligned, as shown in FIGURE 7 to preclude the wasteful loss of wood filler material therethrough.

Although valve means 34 has been described in conjunction with a void filling machine for plywood sheets, it should be apparent that valve 34 has application in other environments.

It will now be seen that there is herein provided an improved valve which is especially adapted for detecting and filling voids in the side edges of plywood or other sheet material, which satisfies all of the objects of the instant invention and others, including many advantages of great practical utility and commercial importance.

Since many embodiments may be made of this inventive concept, and since many modifications may be made of the embodiments hereinbefore shown and described, it will be understood that all matter herein is to be interpreted merely as illustrative, and not in a limiting sense.

I claim:

1. In combination, a valve and a valve holder, said valve holder having an upper and a lower surface and forming an opening connecting said upper and lower surfaces;

said valve comprising a member having an upper and a lower end, a longitudinal axis, an opening parallel to said longitudinal axis, a transverse slot adjacent said lower end communicating with said opening, means closing said opening at said lower end of said member, said member further including a vertically disposed slot adjacent its said lower end;

first means slidably mounted on said member adjacent its said lower end, said first means including an opening disposed adjacent said vertically disposed slot; means securing said first means in said opening of said valve holder adjacent its said lower surface, said securing means including a detent disposed in said opening of said first means, and means disposed adjacent said detent urging said detent into said vertically disposed slot, means in said opening of said valve holder for engagement with means on said member for limiting the downward movement of said member; second means slidably mounted on said member adjacent its said upper end; means securing said second means in said opening of said valve holder adjacent its said upper surface; and means biasing said member downwardly.

2. The structure of claim 1 wherein said means closing said opening of said member provides an upwardly slanting surface underlying said vertically disposed arcuate slot.

3. The structure of claim 1 wherein said member forms a transverse slot communicating with said opening adjacent said lower end, said first means being formed with a transverse slot residing in the same vertical plane as said slot in said member, said valve holder being formed with an opening communicating between said slot of said first means and said lower surface of said valve holder.

4. The structure of claim 3 wherein a sensing means is formed on said lower end of said member.

5. The structure of claim 4 wherein said sensing means comprises a downwardly extending blade of lesser thickness than said member.

6. The structure of claim 3 wherein said biasing means includes abutment means on said member, and

3,355,144

5

resilient means interposed between and engaging said
second means and said abutment means.
